[57] CLAIM

The ornamental design for a crayon protector, as shown and described.

DESCRIPTION

FIG. 1 is an environmental perspective view of a crayon protector showing my new design;

FIG. 2 is a front elevational view thereof, the rear elevational view being a mirror image;

FIG. 3 is an environmental end elevational view thereof, the opposite end elevational view being a mirror image;

FIG. 4 is a top plan view thereof; and,

FIG. 5 is a bottom plan view thereof.

The portion of the figure shown in broken lines in FIGS. 1 and 3 represents a crayon and forms no part of the claimed design.
